UNITED STATES PATENT OFFICE.

HENRY A. MINER, OF MALDEN, MASSACHUSETTS.

DESIGN FOR A COIN-TRAY.

SPECIFICATION forming part of Design No. 27,891, dated November 23, 1897.

Application filed February 27, 1897. Serial No. 625,422. Term of patent 7 years.

To all whom it may concern:

Be it known that I, HENRY A. MINER, a citizen of the United States, residing at Malden, in the county of Middlesex and State of Massachusetts, have invented and produced a new and original Design for Coin-Trays, of which the following is a specification, reference being had to the accompanying drawings, forming a part thereof, wherein—

10 Figure 1 is a view in perspective of the coin tray or plate, and Fig. 2 is a view in elevation thereof.

The leading features of my design consist in the circular plane surface A of the tray or 15 plate, the upwardly-extending inclined surface B, surrounding it, the rounded corner b, and the thick edge b'.

The design has also the flat or plane under surface C and the rounded extensions c.

Having thus fully described my invention, 20 I claim and desire to secure by Letters Patent of the United States—

The design for a coin-tray herein shown and described, comprising the annular rim b having the straight edge b', the outwardly-rounded upper corner, the angular lower corner, the downwardly-sloping top B, the flat depressed central section A, the flat bottom C and the rounded supports c.

HENRY A. MINER.

In presence of—

J. M. DOLAN,
L. A. WALSH.
